UNITED STATES PATENT OFFICE.

LOUIS FRIESS, OF NEW YORK, N. Y.

INDICATOR FOR DUMB-WAITERS, &c.

SPECIFICATION forming part of Letters Patent No. 426,257, dated April 22, 1890.

Application filed January 21, 1890. Serial No. 337,635. (No model.)

To all whom it may concern:

Be it known that I, LOUIS FRIESS, of the city, county, and State of New York, have invented a new and useful Improvement in Indicators for Dumb-Waiters and Elevators, of which the following is a full, clear, and exact description.

This invention relates to improvements in indicators for dumb-waiters and similar devices, and has for its object to provide a simple, convenient, and reliable device of the character named which will automatically indicate the location of the dumb-waiter or elevator at any point of its ascent or descent, the indicating device being placed at the bottom of the shaft.

To these ends my invention consists in certain features of construction and combinations of parts, as is hereinafter described, and indicated in the claim.

Reference is to be had to the accompanying drawings, forming a part of this specification, in which similar letters of reference indicate corresponding parts in all the figures.

Figure 1 is a front elevation of the vertical shaft of an elevator or dumb-waiter with the elevator or dumb-waiter therein, the indicator which exhibits the relative position of the dumb-waiter or elevator being shown in position. Fig. 2 is a sectional side elevation of the same, taken on the line 2 2 in Fig. 1. Fig. 3 is a plan view of the same. Fig. 4 is a transverse section of the same, taken on the line 4 4 in Fig. 1; and Fig. 5 is a transverse section of the same, taken on the line 5 5 in Fig. 1.

In high buildings used for family living purposes it is usual to provide a means for elevation from the ground floor of material needed on the different floors above, these being usually known as "elevators" or "dumb-waiters." As ordinarily constructed in apartment houses or flats, there is no means furnished to exhibit to an operator below the exact position of the dumb-waiter or elevator-car when in use, and to approximately ascertain this relative location of the dumb-waiter an operator on the ground floor must insert the upper portion of his body in the shaft and look up, thereby incurring danger from the possible fall of the heavy box or dumb-

waiter or have dust and dirt thrown down into his eyes.

The device herein represented and about to be described obviates the danger and inconvenience mentioned and exhibits to an operator at the foot of the shaft the exact position of the dumb-waiter at any point from the foot to the top of the building.

A represents the ordinary rectangular vertical shaft or transit passage provided for the dumb-waiter B, that is of the ordinary form, being a rectangular box which loosely fits the shaft A, and is provided with a laterally-projecting lug d, which is adapted to slide in a T-shaped vertical groove a', formed in the side of the shaft A, said box being open at the front to receive articles. The dumb-waiter B is suspended by a flexible rope or chain b from the top of the shaft, said rope extending from the upper side of the box to engage a grooved pulley c', carried on a shaft c, thence laterally to another pulley c², secured to rotate with a shaft c³, thence downwardly to have connection with a weight d, that is of proper size to counterbalance the box or dumb-waiter B, which by equipoise thus afforded may be readily moved to any point vertically considered.

To provide means for vertical movement of the dumb-waiter B within the shaft A, the metal shaft c, whereon the pulley c' is mounted, extends from the rear wall of the hollow shaft A forwardly, and is journaled at e in said wall and forwardly on a cross-bar e', which is stably located at the top of the dumb-waiter shaft A, across its front engaging the side walls of the same, an intermediate cross-bar e² being also provided for support of the shaft c and other parts, as will be explained.

On the front projecting end of the shaft c a grooved pulley f is secured, which receives an endless cord f', the double parallel strands of which are also engaged and held taut by a similar grooved pulley g at the base of the shaft A, so that a movement of the cord f' will cause the dumb-waiter B to ascend or descend the shaft A, as may be required, this being the usual means provided for the reciprocation of the dumb-waiter or elevator-car B.

The indicating mechanism, which coacts with the hoisting apparatus of the dumb-waiter B to exhibit at the base of the shaft A the exact position of said dumb-waiter, will now be described. On the intermediate cross-bar e^2 a standard h is erected, which is located opposite a bracket-block h' on the rear wall of the hollow shaft A, and on the standard and block a short drum-shaft i is journaled by its ends, so as to revolve parallel to the shaft c of the elevating mechanism.

A comparatively large grooved pulley i' is secured on the forward end of the drum-shaft i near the standard h , which pulley is in alignment with a small grooved pulley m on the shaft c of the elevator mechanism, a taut band m' , placed on said pulleys, being adapted to transmit motion from the shaft c when the dumb-waiter is moved and suitably reduce the speed of the drum-shaft i . The upper end of a rope or cord n is secured on the shaft i , around which it is designed to be wrapped, and thence to engage a grooved pulley o , which is pivoted upon the rear side of the upper portion of the weighty sliding block o' , and thence upwardly to be secured by its other end to the regulator-shaft p , around which said end portion of the rope or cord may be wrapped by revoluble movement of the small hand-wheel p' thereon, secured in a position convenient for regulation from one of the floors of the building, which latter are represented by numerals on the side edges of the elevator-shaft A.

An indicator face-plate r is provided for reception of the names of occupants of the different floors in the building, and the numbers

of said floors may also be placed in regular rotation from the lower floor upwardly on the face-plate. A vertical slot is made in the face-plate r , wherein a stud bearing an index or pointer r' may slide, which stud projects from the heavy slide-block o' , and thus by the relative position of the pointer opposite the marks on the face-plate r indicates the position of the dumb-waiter or elevator-car above it.

Should the cord n become slackened or stretch so as to improperly locate the pointer r' , this may be corrected by an adjustment of the regulator-shaft p in an obvious manner.

Having thus described my invention, what I claim as new, and desire to secure by Letters Patent, is—

The combination, with an elevator-car or dumb-waiter, a flexible connection, a counter-balance for the dumb-waiter or elevator-car, and an endless rope which is adapted to move the dumb-waiter or elevator-car reciprocally, of a speed-reducing drum revolubly supported above, a pulley on the drum-shaft flexibly connected to the reciprocating device of the elevator-car, an indicating-plate below, a weighted slide-block having an index-pointer, a loose pulley thereon, and a flexible connection between this pulley and the speed-reducing drum, and also between the loose pulley and a revoluble regulating-shaft of the indicator mechanism, substantially as set forth.

LOUIS FRIESS.
